UNITED STATES PATENT OFFICE

2,495,056

CAN OPENER AND CLOSURE DEVICE

Detlef H. Dauel, Toledo, Ohio

Application January 22, 1947, Serial No. 723,479

4 Claims. (Cl. 220—51)

1

This invention relates to can openers and is more particularly adapted to operate on the type of metal containers commonly used in packaging condensed or evaporated milk for household use.

An object of this invention is to provide a device which pierces two substantially diametrically spaced openings through one end of the can and may remain mounted on the container during its use permitting discharge of the contents or sealing the openings at will.

An additional object of the invention is to provide a device of the class described which not only effects the piercing of the can but which may be manually manipulated to simultaneously and completely open both openings for free discharge of the can's contents from either thereof and then to automatically completely seal both openings during storage and after each pour.

Still another object of the invention is to provide a device of the class described which maintains the openings free from any accumulations or content coagulations which would tend to dam the apertures and to prevent foreign matter entering the can during storage.

An additional object of the invention is to provide means which may easily be brought into cooperation with the piercing arms to augment their piercing force.

Other objects and advantages of this invention relating to the arrangement, operation and function of the related elements of the structure, to various details of construction, to combinations of parts and to economies of manufacture, will be apparent to those skilled in the art upon consideration of the following description and appended claims, reference being had to the accompanying drawings forming a part of this specification wherein like reference characters designate corresponding parts in the several views.

Referring to the drawings:

Fig. 1 is a side elevation of a condensed milk can or the like having the device of the invention mounted thereon;

Fig. 2 is a plan view of the showing of Fig. 1;

Fig. 3 is a plan view of a pierced can, with the device removed, showing the aperture relationship;

Fig. 4 is a view on the line IV—IV, Fig. 2, showing the auxiliary lever or pry in position to augment the normal piercing operation; and

Fig. 5 is a fragmentary side elevation with the parts in pouring position.

Base plate 10 is herein shown as a substantially Y-shaped sheet metal stamping having a plurality of spring fingers 12 extending from the legs

2

thereof and designed to grip the periphery of container 13. The container is of the type used to package condensed or evaporated milk and the fingers are preferably three in number which efficiently grip the can and securely hold the plate against can end 16.

The plate 10 is provided with a pair of rearwardly extending offsets as to the fingers or outwardly extending from the container. These offsets 18 are so positioned as to be substantially aligned and spaced along a diametrical line across the can end 16 when the device is in operating position. These offsets 18 provide bearings or mounting means for a pair of fulcrums herein shown as rivets 20 mounting piercing arms 22 intermediate their length, each arm having a punch portion or piercing head 24 on the remote termini thereof. These arms 22 are mounted to extend toward and overlap each other and in operation simultaneously rock on their respective fulcrum 20 and to this end one of said arms is provided with a slot 26 while the other arm has offset or lug 28 extending into and cooperating with the slot. There is thus provided an interlocking connection between the arms.

A trigger or finger-nest 30 is mounted on one of said arms and when depressed causes operation of both arms due to the interlocking or interconnection between the slot and lug.

In use, the device is placed in position relative to the container to have the piercing heads contact the container head at two diametrically disposed points. Then the device is thrust against the can and the heads 24 pierce or punch two apertures 52 in the can, simultaneously seal the same and bring the plate 10 to rest against such container end. The device is now ready for use. As it is desired to pour the container contents therefrom, it is only necessary to grip the container and press the trigger 30 which causes both apertures to be opened and the can contents can freely flow from either thereof as the other serves as a vent.

Upon completion of a pour, the trigger 30 is released and spring 34 extending between one of said arms 22 and the base 10 resets the parts causing the punches to again seal the apertures thereby preventing contamination of the can contents or any accumulations therein due to coagulation of the contents.

In instances wherein it is desired to augment the container piercing and device mounting operation, pry or lever 36 is provided having lugs 38 which may engage either arm so that the pry may serve as a positive forcing means (Fig. 4) in aid-

ing the initial can opening operation. This pry is so designed as to securely grip either arm on either side thereof as illustrated.

During the periodical use of the contents of the container, the pry may be hung on hook 40 which is conveniently provided as an extension of one of the fingers 12. In normal use, the thumb of a user grips this pry against the container when the container is held so there is no interference therefrom during the pour. A finger on the same hand can conveniently operate the trigger.

It is to be understood that the above detailed description of the present invention is intended to disclose an embodiment thereof to those skilled in the art, but that the invention is not to be construed as limited in its application to the details of construction and arrangement of parts illustrated in the accompanying drawings, since the invention is capable of being practiced and carried out in various ways without departing from the spirit of the invention. The language used in the specification relating to the operation and function of the elements of the invention is employed for purposes of description and not of limitation, and it is not intended to limit the scope of the following claims beyond the requirements of the prior art.

What is claimed and it is desired to secure by United States Letters Patent is:

1. In a device of the class described, a base plate, spring fingers extending from said plate for engaging a container upon which the device is mounted, a pair of bearings carried by said plate, an arm intermediately mounted by each bearing and providing a pair of piercing heads on the remote termini thereof with portions extending toward and overlapping each other, one of said arms being provided with a slot and the other arm having an offset engaging said slot, and an operating trigger carried by one of said arms.

2. In a device of the class described, a base plate, spring fingers extending from said plate for engaging a container upon which the device is mounted, a pair of bearings carried by said plate, an arm intermediately mounted by each bearing and providing a pair of piercing heads on the remote termini thereof with portions extending toward and overlapping each other, one of said arms being provided with a slot and the other arm 50

having an offset engaging said slot, an operating trigger carried by one of said arms, and spring means coacting to normally urge said arms toward container piercing position.

5. The structure set forth in claim 2 wherein said spring is connected between one of said arms and the base plate.

4. In a device of the class described, a sheet metal stamping substantially Y-shaped with a spring finger offset in one direction from the terminal of each leg thereof and adapted to grip the periphery of a container to mount and locate said plate against the container end, said stamping additionally provided with a pair of offsets 15 extending in the opposite direction as to the spring fingers and disposed in alignment adjacent a diameter of the container end, a pair of sheet metal stampings providing arms, each thereof intermediately and rockably mounted on one of said 20 offsets, said arms being configured at their remote termini to provide container piercing heads and closing means for apertures formed by the piercing operation, said arms having their portions remote from the piercing portions overlap 25 with one thereof provided with a slot therein and the other an offset extending into said slot, one of said arms continuing beyond the offset and slot engagement to provide a trigger which when depressed causes both piercing heads to be raised 30 from their container engaging positions, and spring means coacting between one of said arms and the plate to cause said heads to reengage the container and close said apertures upon release of the trigger.

DETLEF H. DAUEL.
